UNITED STATES PATENT OFFICE.

HARRY A. PALMER, OF JACKSON, MICHIGAN, ASSIGNOR TO REYNOLDS SPRING COMPANY, OF JACKSON, MICHIGAN.

CRIMPING MACHINE.

Application filed December 8, 1921. Serial No. 521,018.

To all whom it may concern:

Be it known that I, HARRY A. PALMER, a citizen of the United States, residing at Jackson, in the county of Jackson and State 5 of Michigan, have invented new and useful Improvements in Crimping Machines, of which the following is a specification.

The invention relates to a crimping machine.

10 Heretofore U-bars have been secured to coiled springs at opposite sides thereof by crimping or compressing the U-bars on the coils or convolutions of the springs but as this operation has been performed manually 15 with a hand tool the attachment of the U-bars to the springs has not been uniform, owing to the springs being not equi-distantly spaced and due to the U-bars being unequally crimped or compressed, resulting in a 20 laborious operation and an unsatisfactory structure. Also the crimping or compressing of the U-bars is not always at diametrically opposite points and frequently through the tiring of the hand the U-bars 25 are not properly crimped or compressed and a loose joint or connection sometimes results from such defective compressing or crimping of the U-bars.

The object of the present invention is to 30 provide a simple, practical and efficient crimping machine of strong, durable and comparatively inexpensive construction adapted to obviate the foregoing objections and to compress U-bars onto springs and 35 capable of simultaneously and uniformly crimping or compressing U-bars at opposite sides of a plurality of properly spaced springs at the desired points, diametrically opposite each other at the base or other coils 40 or convolutions of the springs, whereby a pair of U-bars is secured to a plurality of springs at opposite sides thereof with requisite accuracy.

With these and other objects in view the 45 invention consists in the construction and novel combination and arrangement of parts hereinafter fully described, illustrated in the accompanying drawings and pointed out in the claims hereto appended, it being understood that various changes in the form, proportion and minor details of construction, within the scope of the claims, may be resorted to without departing from the

spirit or sacrificing any of the advantages 55 of the invention.

In the drawings, in which like characters of reference designate corresponding parts in the several views:

Figure 1 is a side elevation, partly in section, of a crimping machine constructed in 60 accordance with this invention.

Fig. 2 is an end elevation of the same.

Fig. 3 is an end view of a portion of the machine, illustrating the arrangement of the 65 gearing for connecting the cam shafts.

Fig. 4 is an enlarged plan view of one side of the crimping mechanism.

Fig. 5 is a longitudinal sectional view of the same.

Fig. 6 is a transverse sectional view on 70 the line 6—6 of Fig. 5.

Fig. 7 is a plan view of one of the spring supporting members or pegs.

Fig. 8 is a side elevation of the same.

Figs. 9 and 10 are detail views of the 75 clutch actuating member.

Figs. 11 and 12 are enlarged plan views of the inner and outer crimping dies.

Fig. 13 is a vertical sectional view of the spring holding means illustrating the 80 interior structure thereof and the means of mounting the same.

Fig. 14 is an enlarged fragmentary view illustrating the spring holding means and the dies for compressing the spring connecting bars onto the spring.

Fig. 15 is a similar view showing the dies of the crimping mechanism in operative position for crimping action.

Fig. 16 is a horizontal sectional view 90 through a completed article showing the spring connecting bars connected to a row of springs,—illustrating the result of operation of the machine.

In the accompanying drawings, in which is illustrated the preferred embodiment of the invention, the crimping machine comprises in its construction a frame composed of end members 1 supporting a bed plate 2 and connected at the bottom by centrally arranged longitudinal rod 3 and by a rear longitudinal shaft or pivot 4, but the frame may be constructed and braced in any other desired manner as will be readily understood and the machine may be made of any desired size and capacity to suit the char-

acter of spring structures in which the coiled springs and connecting U-bars are used. The bed plate, which forms the top of the machine, is provided at its corners with 5 posts or pedestals 5 extending upwardly and supporting longitudinal cam shafts 6 and 7 journaled in suitable bearings 8 of the posts or pedestals and provided at intervals with double cams 9 arranged to simultaneously 10 actuate upper and lower reversely reciprocating slides 10 and 11 arranged in pairs at opposite sides of a central spring supporting member or peg 12, and carrying inner and outer dies 13 and 14 which are arranged to 15 engage and crimp or compress the U-bars on the base coils or convolutions of the springs. Each spring A is supported by the respective peg 12 in such a manner as to place or suspend the base convolution below the peg 20 and between the respective inner and outer dies as shown particularly in Figs. 14 and 15. The cams, the die, carrying the slides or members, and the spring supporting peg or member constitute a set of crimping 25 mechanisms and in practice the machine may be equipped with any number of sets of such mechanism to provide a machine of the required capacity, that is, for the connection of as many springs as required to the spring 30 supporting and connecting bars B, one of said mechanisms for each spring.

As shown in Fig. 16, wherein is embodied one of the products derived from the present machine, the machine is designed to fasten 35 a row of spaced springs A to their supporting bars B, the latter being continuous U-shaped strips composed of sheet metal and arranged in pairs to receive opposite sides of the base convolutions of the springs in 40 which the base coils are fastened by crimping or compressing the flanges of the bars firmly onto the base convolutions at opposite sides thereof as evidenced in the finished article illustrated in Fig. 16. The 45 row of springs thus connected to the pair of bars provides a unit to form part of an automobile, car, or other spring seat structure. The machine illustrated shows but one support in the machine for a spring and but one crimping mechanism, but in practice, a number of springs are mounted in the 50 machine and connected to the U-shaped bars at one operation, to produce such an article as that shown in Fig. 16, depending upon 55 the length of row desired, but as each individual crimping mechanism and spring support is the same and arranged in alignment and operated from one and the same means, it has been deemed sufficient to illustrate 60 the one supporting and the one crimping mechanism, which is believed sufficient to disclose the invention without unnecessary duplication of parts. To this end, each crimping mechanism is mounted in a housing 65 15 extending across the machine from

front to rear and bolted or otherwise secured to the bed plate at the front and back thereof, as clearly illustrated in Fig. 5 of the drawings. The cams are keyed or otherwise fixed to the cam shafts 6 and 7 and each 70 cam is a double cam and is provided at diametrically opposite points with cam portions adapted to simultaneously actuate the said slides 10 and 11 for moving the upper slide inwardly and the lower slide outwardly in 75 the crimping operation. The housing 15 which is provided at the top with cover plates 16 form longitudinal guiding recesses 17 and are provided at the bottom thereof with supporting ledges 18 and have lower 80 extensions 19 to receive reinforcing ribs or flanges 20 of the lower slides 11 (see Fig. 6). The upper slide at each side of the central spring supporting peg or member is arranged upon the lower slide, which is supported upon the said ledges 18, as clearly 85 illustrated in Fig. 6 of the drawings, and the said upper slide is composed of inner and outer sections 21 and 22, which are connected by a right and left hand threaded adjusting screw 23 having a central enlargement or operating portion 24 and threaded into suitable sockets 25 and 26 of the inner and outer sections of the upper slide, and the 90 said right and left hand threaded screw 23 is adapted to be rotated to adjust the sections of the slides toward and from each other to vary the length of the slide and the position of the die 14 with relation to the die 13. The screw 23 is secured in its adjustment by means of a lock nut 27 which is mounted on the inner portion of the screw 23 for engaging the adjacent end of the inner section 21 of the upper slide, but any 95 other suitable means may, of course, be employed for securing the adjusting screw and the sections of the upper slide in its adjustment. The outer section of the upper slide is bifurcated at its outer end to receive an anti-friction wheel 28 which is engaged 100 by the cam 9, and the inner end of the inner section 21 of the upper slide 10 is recessed at 29 to receive the die 14 which is provided at its inner end with a depending lug or flange 30 fitting in an extension of 105 the recess 29 and adapted to hold the die against relative longitudinal movement whereby when the upper slide is assembled 110 and the top plate 16 secured in position, the die 14 will be rigidly connected to the inner end of the upper slide and will move with the same in the operation of the machine. The die 14 which projects beyond the inner end of the upper slide is provided 115 in its projecting or engaging portion with a groove or recess 31, forming approximately U-shaped walls to conform to the configuration of the U-bars to be crimped and having its walls formed by substantially 120 parallel upper and lower portions and a 125

concave connecting inner portion, as clearly illustrated in Figs. 5, 12 and 14 of the drawings.

The co-acting inner dies 13 is provided in its projecting or engaging portion with a substantially V-shaped recess or groove 32 which forms upper and lower inwardly converging walls adapted to engage the sides or flanges of the U-bar and compress or 10 crimp the same around the coils or convolutions of the springs. The die 13 has its inner portion laterally reduced to form a projecting tongue 33 (see Fig. 11) and the projecting and engaging portion of the co- 15 acting die 14 is centrally recessed at 34 to provide side projecting portions 35 which are located at opposite sides of the centrally projecting portion or tongue 33 of the inner die 13 when the dies close upon the 20 U-bar in the crimping action of the machine. In the crimping or compressing operation the dies inter-fit and the metal is accurately and uniformly crimped or compressed and the U-bars are firmly secured to 25 the springs.

The inner crimping die 13 fits upon the inner end of the lower slide, which is provided in the upper face of its inner end with a dove-tailed recess 36 to receive a depending dove-tailed flange or rib 37 of the inner die 13, whereby the inner die 13 is 30 slidably interlocked with the inner end of the lower slide 11. The lower slide 11 which extends beneath and forms a support for the upper slide 10 is approximately T-shaped in cross section, as illustrated in Fig. 6 of the drawings, to provide laterally projecting side portions to rest upon the ledges 18 of the housing 15 and the rib or depending portion 20 extends along the longitudinal center of the upper laterally extending portion. The inner end of the lower slide extends upwardly to arrange the upper face of its inner end in flush relation with the 40 upper face of the recessed inner end of the upper slide and the lower slide is also provided at its outer portion with a curved arm or extension 38 which is located beneath the cam shaft and the cam 9 and which has its outer terminal portion bifurcated to receive an anti-friction wheel 39 which is located diametrically opposite the anti-friction wheel 28 of the upper slide. The cam 9 operates between the anti-friction 45 wheels 28 and 39 and when the cam shaft is rotated the cam 9 is carried from the position illustrated in Figure 5 of the drawings and rotated through one-half of a revolution to move the upper slide inwardly and the lower slide outwardly and thereby compress or crimp the U-bar of the spring. The lower slide is provided in the upper 50 face of its central body portion with a longitudinal recess 40 in which is arranged a coiled spring 41 interposed between the in-

ner end of the longitudinal recess 40 and a depending projection 42 of the outer section of the upper slide and adapted to be compressed by the inward movement of the upper slide and the outward movement of the lower slide and to force the said slides inwardly and return the same to their initial position as the opposite cam operations of the double cam recede in the rotation of the cam shaft. 75

The dies are arranged in pairs at opposite sides of the central spring supporting peg or member, which is mounted upon the central portion of the housing and which is provided at the base with a central recess 43 into which extends the inner portions of the lower slides of the set of crimping mechanism. The central spring supporting peg or member 12 is provided at opposite sides of the recess 43 with projecting flanges or portions 44 which are seated upon the housing at opposite sides thereof and the said housing is provided with a central circular recess 45 formed by enlarging the longitudinal guide and receiving the lower portions 46 of the spring supporting peg or member. The portions 46 which are located at opposite sides of the recess 43 have curved or rounded outer faces to conform to the configuration of the central chamber or recess 45 of the housing. The peg or supporting member 12 is tapered, as shown, and it is adapted to vary in size to adapt it for supporting the character of spring to which the U-bars are to be attached and the said peg or spring supporting member is detachably mounted upon the central portion of the housing and may be readily removed to enable a peg or supporting member of a different size to be substituted for it. 95

The machine is preferably equipped at the front with a guard 47 of sheet metal or other suitable material located at the front and top of the adjacent cams and the cam shafts are connected at one end of the machine by suitable end gears 48 and 49 and intermediate gears 50. The end gears 48 and 49 are mounted on the cam shafts 6 and 7 and the intermediate gears 50, which mesh with each other and with the gears 48 and 49, are mounted on stub shafts or spindles, but any other desired arrangement of gearing or any other suitable form of gearing may be employed for transmitting motion from the rear cam shaft 7 to the front cam shaft 6. The rear cam shaft 7 receives its motion from a driven pulley or fly wheel 51, loosely mounted on the rear cam shaft 7 at one end thereof and adapted to be clutched to the same by means of a slideable clutch member 52 interlocked with the rear cam shaft and actuated by a clutch operating member 53, consisting of a plate or bar secured to and carried by one arm of a bell 100 105 110 115 120 125 130

crank lever 54 and extending upwardly therefrom as clearly indicated in Fig. 2 of the drawings and having a curved upper portion 55 conforming to the configuration of the slideable clutch section and provided with an inclined engaging edge or face 56 adapted to contact with a stud or projection 57, carried by the clutch section 52, whereby when the clutch operating member 53 is moved into engaging position, by the means hereinafter described, the slideable clutch section will be carried out of engagement with the rotating power driven pulley or wheel 51 and will unclutch the rear cam shaft from the same, as hereinafter fully described. Any suitable form of clutch may, of course, be employed and the machine is preferably equipped adjacent the clutch with a band brake 58. The bell crank lever, which is fulcrumed at its angle at 59, has an upwardly extending arm which carries the clutch operating member and the said lever has its other arm extending forwardly and connected by a link 60 with a rearwardly extending terminal arm 61 of a central longitudinal rock shaft 62 journaled in suitable bearings of the end frame members 1 and having a terminal extension on which the arm 61 is mounted, as clearly illustrated in Fig. 2 of the drawings. The central longitudinal shaft 62 is provided with a central forwardly extending arm 63, which is connected at its outer end by a rod 64 with a treadle consisting of a treadle lever 65, pivoted at its rear end 66 on the lower connecting rod or pivot 4 and extending forwardly therefrom and projecting at the front of the machine, as clearly shown in Figure 2 of the drawings. The treadle lever is equipped at its front end with a foot plate 67 adapted to be stepped on by the operator to depress the treadle, which carries with it the forwardly extending arm 63 of the shaft 62, thereby raising the rearwardly extending arm 61 and operating the bell crank lever and the clutch controlling member. The slideable clutch section is spring actuated to move it into engagement with the power driven pulley or fly wheel and the inclined edge of the clutch controlling member is adapted to force the slideable clutch section out of engagement with the power driven pulley or wheel. When the operator steps upon the treadle the upwardly extending arm of the bell crank lever is moved away from the slideable clutch section and the latter is permitted to engage the power driven pulley for rotating the cam shafts to crimp or compress the U-bars and as soon as the operator removes his weight from the treadle the clutch controlling member is returned to its normal position in engagement with the face of the slideable clutch section by means of a spring 68 connected with the arm 61 and with the pivot or connecting rod 4. A spring 69 is also connected with the upwardly extending arm of the bell crank lever 54. In the operation of the machine the operator retains the pressure on the treadle sufficiently to release the clutch section and to permit the same to engage the power driven pulley or wheel and he then removes his weight so that the inclined or beveled face or edge of the clutch controlling member will return to its normal position within the path of the stud 57 and engage the same and force the slideable clutch section out of engagement with the power driven pulley or wheel, as the cam shaft completes the required movement. The band brake 58 may be of any desired construction and it may be operated and controlled by any suitable means and its purpose is to reduce the momentum of the cam shaft. The brake causes the cam shaft to stop on the center and prevents the machine from repeating. The springs and the U-bars may be placed in the machine separately or may be assembled before placing them into the machine.

What is claimed is:

1. A crimping machine including means for holding a spring and suspending its base convolution therebeneath, and a crimping mechanism including dies for operating in the horizontal plane of said base convolution to crimp a bar onto said base convolution.
2. A crimping machine including means for holding a spring and suspending the base convolution freely therebeneath, and a crimping mechanism including cooperating dies arranged for operation in the horizontal plane of said base convolution to crimp bars upon opposite sides of the base convolution.
3. A crimping machine including means for holding a spring with the base convolution thereof suspended on opposite sides thereof and therebeneath, and means whereby to compress a sheet metal member intermediate its ends onto the suspended base convolution of the spring to secure said member to the spring.
4. A crimping machine comprising spring holding means, a crimping mechanism including separate sets of dies, the dies of each set being movable toward and away from each other, means constructed and arranged to force the dies of each set toward each other to compress spring supporting bars onto the spring, and means whereby to move the dies of each set away from each other for said compression action.
5. A crimping machine including means for holding a spring, the holding means being provided with a slot and a crimping mechanism including sets of crimping dies, a die of each set operating in the slot of the holding means, one die of each set having

projecting and engaging portions provided with a groove and the other die of each set being provided with a projecting portion movable between the spaced portions of the 5 companion die and provided with a groove.

6. A crimping mechanism including means for holding a spring, crimping mechanism arranged to carry and to compress a spring supporting bar onto the spring, including 10 sets of dies, the dies of each set being movable toward and away from each other, and a cam mechanism for actuating the crimping mechanism.

7. A crimping machine comprising spring holding means, a crimping mechanism including upper and lower slides having oppositely disposed portions, opposite dies carried by the slides and movable toward and away from each other and arranged to 20 press a spring supporting bar intermediate its ends directly onto a spring, and a double cam located between the opposite portions of the slides for simultaneously moving the same in opposite directions.

25 8. A crimping machine, comprising spring holding means, an upper slide, a lower slide supporting the upper slide and having a terminal extension spaced from one end of the upper slide, a cam operating between 30 said extension and the upper slide, and dies carried by said slides.

9. A crimping machine comprising means for holding a spring, a crimping mechanism including slides, dies carried by the slides 35 and movable toward and away from each other, one of the dies adapted to carry a spring supporting bar and a cam for engaging the slides to move the dies in one direction to effect a crimping of the said bar 40 onto the spring, and a spring interposed between the slides for moving the dies in the opposite direction after the crimping operation.

45 10. A crimping machine including means for holding a spring with the lower convolution of the spring spaced from the holding means, a crimping mechanism including an upper set of slides and a lower set of slides, the former being slidable upon the 50 latter, dies carried at the inner ends of the lower slides and slidable with the latter under the spring supporting means and within the lower convolution of the spring, dies carried by the inner ends of the upper 55 slides and movable toward and away from the lower convolution of the spring in horizontal alinement with the aforementioned dies and constructed to carry spring supporting bars, and means constructed and arranged 60 and operatively connected to said slides to move the same in opposite directions toward each other to carry said bars to the lower convolution of said spring and crimp the bars onto the lower convolution of the 65 spring.

11. A crimping machine including means for holding a spring with the lower convolution of the spring spaced from the holding means, a crimping mechanism including an upper set of slides and a lower set of slides, 70 the former being slidable upon the latter, dies carried at the inner ends of the lower slides and slidable with the latter under the spring supporting means and within the lower convolution of the spring, dies carried 75 by the inner ends of the upper slides and movable toward and away from the lower convolution of the spring in horizontal alinement with the aforementioned dies and constructed to carry spring supporting bars, and a double cam mechanism arranged to move the sets of dies toward each other to carry 80 the bars to the lower convolution of the spring and compress the bars on opposite sides of the spring.

85 12. A crimping machine including means for holding a spring with the lower convolution of the spring spaced from the holding means, a crimping mechanism including an upper set of slides and a lower set of slides, 90 the former being slidable upon the latter, dies carried at the inner ends of the lower slides and slidable with the latter under the spring supporting means and within the lower convolution of the spring, dies carried 95 by the inner ends of the upper slides and movable toward and away from the lower convolution of the spring in horizontal alinement with the aforementioned dies and constructed to carry spring supporting bars, and 100 means constructed and arranged and operatively connected to said slides to move the same in opposite directions toward each other to carry said bars to the lower convolution of said spring and crimp the bars onto 105 the lower convolution of the spring, and a spring connection between each set of upper and lower slides whereby to return the slides to normal position after the compressing operation.

110 13. A crimping machine including means for holding a spring with the lower convolution of the spring spaced from the holding means, a crimping mechanism including an upper set of slides and a lower set of slides, 115 the former being slidable upon the latter, dies carried at the inner ends of the lower slides and slidable with the latter under the spring supporting means and within the lower convolution of the spring, dies carried 120 by the inner ends of the upper slides and movable toward and away from the lower convolution of the spring in horizontal alinement with the aforementioned dies and constructed to carry spring supporting bars, 125 and a double cam mechanism arranged to move the sets of dies toward each other to carry the bars to the lower convolution of the spring and compress the bars on opposite sides of the spring, and a spring con- 130

nection between each set of upper and lower slides whereby to return the slides to normal position after the compressing operation.

14. A crimping machine including spring holding means, slides located at opposite sides of the spring holding means and provided at their inner ends with dies, cam shafts extending longitudinally of the machine and located at the outer ends of the slides, rollers carried by the outer ends of the slides, a gear mechanism between said cam shafts, and cams on the cam shafts located between the respective rollers of the slides for actuating the latter.

15. 15. A crimping machine, including spring holding means, slides located at opposite sides of the said means and provided at their inner ends with dies, cam shafts extending longitudinally of the machine and located at the outer ends of the slides, gearing connecting the cam shafts and arranged at one end of the machine, and cams on the cam shafts for actuating the slides.

16. A crimping machine, including spring holding means, slides located at opposite sides of the spring holding means and provided at their inner ends with dies, cam shafts extending longitudinally of the machine and arranged at the outer ends of the slides, cams mounted on the shafts for actuating the slides, gearing connecting the cam shafts, a power wheel mounted on one of the cam shafts, a movable clutch member for clutching the power wheel to the said cam shaft, and means for operating the clutch member.

17. A crimping machine, including spring holding means, slides located at opposite sides of the spring holding means and provided at their inner ends with dies, cam shafts extending longitudinally of the machine and arranged at the outer ends of the slides, cams mounted on the shafts for actuating the slides, gearing connecting the cam shafts, a power wheel mounted on one of the cam shafts, a movable clutch member for clutching the power wheel to the said cam shaft, and means for operating the clutch member, said operating means comprising a projection on said clutch member and a controlling member movable into and out of the path of the projection and having an inclined edge for engaging the same to move the clutch member away from the power wheel.

18. A crimping machine, including spring holding means, slides located at opposite sides of the spring holding means and provided at their inner ends with dies, cam shafts extending longitudinally of the machine and arranged at the outer ends of the slides, cams mounted on the shafts for actuating the slides, gearing connecting the cam shafts, a power wheel mounted on one of the cam shafts, a movable clutch mem-

ber for clutching the power wheel to the said cam shaft, and means for operating the clutch member, said operating means comprising a projection carried by the clutch member, a bell-crank lever having a clutch controlling member movable into and out of the path of the said projection and provided with an inclined edge for engaging the same to move the clutch member away from the power wheel, a rock-shaft connected with the bell-crank lever, a pedal for operating the rock-shaft, and a spring connected with the rock-shaft for returning the operating mechanism to its initial position.

19. A crimping mechanism including means for holding a spring with its lower convolution free, a set of dies slidable within the lower convolution of the spring toward and away from opposite sides thereof, a set of dies exterior of the spring, one on each side thereof and opposite the respective aforesaid dies and slidable in cooperative alinement with the aforesaid dies and constructed to carry spring supporting bars, means for sliding said sets of dies toward each other to place the bars adjacent to the lower convolution of the spring and to effect a compression of the bars onto the spring, and means for moving the sets of dies away from each other after the compression operation.

20. A crimping mechanism including means for holding a spring with its lower convolution free, a set of dies slidable within the lower convolution of the spring toward and away from opposite sides thereof, a set of dies exterior of the spring, one on each side thereof and opposite the respective aforesaid dies and slidable in cooperative alinement with the aforesaid dies and constructed to carry spring supporting bars, means for sliding said sets of dies toward each other to place the bars adjacent to the lower convolution of the spring and to effect a compression of the bars onto the spring.

21. A crimping machine, including means for holding a spring with its lower convolution free, a set of dies slidable toward and away from each other into and out of engagement with the inner sides of the lower convolution of the spring, dies constructed and arranged to hold and present spring supporting bars to opposite sides of the lower convolution of the spring and to contact with the first-mentioned dies to compress the spring supporting bars onto the lower convolution of the spring, and means for operating the aforesaid dies to effect said compression action.

22. A crimping machine, including means for holding a spring with its lower convolution free, a set of dies slidable toward and away from each other into and out of engagement with the inner sides of the low-

er convolution of the spring, dies constructed and arranged to hold and present spring supporting bars to opposite sides of the lower convolution of the spring and to co-act 5 with the first mentioned dies to compress the spring supporting bars onto the lower convolution of the springs, and cam mechanism to operate said dies to effect said compression action.

23. A crimping machine including means 10 for holding a spring and suspending its base convolution therebeneath, and a crimping mechanism arranged to crimp a sheet metal U-bar into embracing relation with said base convolution. 15

In testimony whereof I have hereunto set my hand.

HARRY A. PALMER.
